ROTARY CASTING.

1,329,295.

Specification of Letters Patent. Patented Jan. 27, 1920.

Application filed March 3, 1919. Serial No. 280,452.

To all whom it may concern:

Be it known that I, DIMITRI SENSAUD DE LAVAUD, a citizen of the United States of Brazil, residing at New York, in the county 5 of New York and State of New York, have invented certain new and useful Improvements in Rotary Casting, of which the following is a specification.

This invention relates to the art of utilizing 10 a rotary mold for the casting of hollow metallic articles, preferably partly centrifugally; the invention being particularly applicable to the casting of annular articles of considerable length as compared with 15 their diameter.

As it well known, rotary casting machines as heretofore constructed have comprised broadly a rotary mold and a trough, spout, runner or gate for feeding the molten metal 20 into the interior of the rotating mold. In some cases, as is desirable for casting elongated annular articles, the mold and trough or spout have been relatively movable axially of the mold; but in all such cases, as far 25 as I am aware, when the feeding means was a trough, the relative movement between mold and trough has been primarily for completely overlapping the trough by the mold before spilling the metal from the 30 trough into the mold and where the feeding means has been a spout, the spout has been so designed at its continuously open discharge end that the metal has either been discharged into the mold in spirally laid 35 subdivisions in a curve of flow reaching the mold at a slight angle in the vertical plane containing the axis of the mold, or the flow of metal has been substantially annular or shaped like the fraction of an annulus so 40 that the metal reaches the mold at a very slight angle to the axis of the mold and on both sides of the axis of the mold. By the statement that the flow of metal contacts the mold is of course meant that the flow 45 of metal directly contacts the mold, as at the beginning of the laying in the mold of the spirally related subdivisions of metal, or that the flow of metal practically reaches the mold on merging with the previously 50 laid spiral subdivisions of the molten metal. Neither of these previous systems is practical for the making of commercial articles, say pipe, because neither case satisfies a discovery which I have made as to the ideal 55 conditions under which the molten metal should be laid in the mold, which is to say

that the molten metal should be delivered downwardly and at one side only of the axis of the mold and at a velocity such that its velocity at the instant of reaching the 60 mold is substantially the same as or bears a definite relation to the peripheral velocity of the inside of the mold; preferably, the metal being delivered at such speed and at such inclination of stream-flow relative to 65 the inner periphery of the mold and its direction of rotation, that the force of the stream as it impinges against the mold is great enough to insure that practically all 70 the metal at any instant being delivered to the mold is flung against the mold and travels under its own momentum with the mold's inner periphery at least until the combined effect of centrifugal force and intermolecular friction within said metal func- 75 tions to maintain said metal fixed relative to previously deposited metal. The explanation of this is, I now believe, that if the molten metal is not delivered in this manner a churning or concrete-mixer effect is set 80 up, and, moreover, globules of molten metal are thrown out and up in the mold and partially congeal while in the air and so result in a multiplicity of more or less uniformly distributed half-round teats on the 85 inside of the pipe, and if the metal is not furthermore discharged at or substantially at the velocity indicated fullest advantage is not taken of another discovery of mine, 90 which is that in this art too much importance 95 has been erroneously ascribed to the pure centrifugal effect as opposed to the recognition, which has not been duly given, of the fact that friction between the molecules of the molten iron delivered and between the 95 iron and the inside of the mold is a factor in at least coöoperating with centrifugal force to spread the metal uniformly around the mold. Consequently, wherever it is 100 stated in the appended claims that the metal is discharged at substantially the velocity of the mold, the meaning is that the metal is delivered as above described.

It will be seen from what follows that the present invention, while it may be advantageously used for the casting of an annular article of any outside diameter as compared with its wall thickness, and an annular article of any metal, as cast iron, is particularly valuable for the casting of annular articles of comparatively small outside diameter and yet of considerable wall 110

thickness, since it is obvious that the use of a trough, which type of feeding means gives so much better results in a mold on a horizontal or substantially horizontal axis that 5 the old spout type of feeding means has been practically abandoned, may not be used at all if it is of sufficiently small outside diameter to clear the predetermined bore of the annular article and at the same time of sufficient capacity to deliver without appreciable pause the amount of molten metal required to provide the large wall thickness.

10 The present invention involves a new process and a novel apparatus which may advantageously be used in carrying out such process, whereby the above discoveries may be taken advantage of and the herein indicated advantages be realized.

15 The process, briefly, may be described as 20 the casting of an annular metallic article in a rotary mold on a substantially horizontal axis, which consists in laying the metal in the mold in successively deposited spirally related subdivisions while guiding the 25 flow of the metal adjacent to the mold to cause the metal to flow in a limited sheet to one side of the mold axis. By the term "substantially horizontal axis" is meant also an axis which is inclined suitably from the 30 horizontal but never being nearer the vertical than the horizontal, whereby if desired another feature of the invention may be taken advantage of, which is the possibility of tilting the mold axis from the horizontal 35 before casting to affect the velocity of the flow of metal in the limited sheet mentioned. Preferably the sheet is so guided as to approach the mold in a path nearer a plane perpendicular to the axis of the mold than 40 a vertical plane containing such axis. Preferably, also, the metal flowing from the feeding means into the mold is so guided that the metal flows into the mold only at one side thereof. Preferably, further, the 45 metal before thus approaching the mold, is guided over a distance substantially axially of the mold, by which is meant that it is guided lengthwise of the mold whereby the feeding means may be conveniently arranged, in an apparatus wherein the mold and trough are relatively movable during 50 the casting, to facilitate forming the annular article by progressively laid spirally related subdivisions of the molten metal. Preferably, also, the metal delivered to the 55 mold has the same velocity, or else as near the same velocity as practical conditions will admit, as the peripheral velocity of the inside of the mold, by which is meant the 60 average peripheral velocity of the inside of the mold where the mold is provided with depressions and elevations to form an annular article having an exterior conformation specially shaped; but in any case best results are obtained when the metal is de-

livered to the mold pursuant to the principles of velocity and direction of stream-flow hereinbefore disclosed. In other words, broadly the preferred process involves directing the sheet of metal to continuously approach the mold at one side of the mold axis only, at a certain minimum speed and at a special inclination.

The preferred apparatus by which this process may advantageously be carried out involves broadly the combination of a rotary mold, a metal distributer of the spout type adapted to project inside the mold and constructed and arranged for continuously discharging molten metal inside the mold, operating means for moving the distributer and mold relatively lengthwise of the mold, movable feeding means, as a tilting reservoir for delivering molten metal to the distributer adapted to be moved or tilted to vary the rate of delivery of molten metal to the distributer, and means controlled by the relative movement of either the distributer or mold and operatively connected to the feeding means for moving the latter constantly to supply molten metal from the feeding means to the distributer in definite relation to the rate of discharge of molten metal by the distributer into the mold. Preferably it is the mold which is moved relative to the trough. Preferably the distributer is an elongated gutter member, provided with a lengthwise canal, with the feeding means arranged to deliver molten metal to the canal adjacent to one end of the latter and with the canal at the opposite end of the distributer angularly bent to one side only of the mold and terminating in an open-spout mouth adapted to direct the molten metal discharged from the distributer in a stream substantially tangentially striking the mold. Preferably the feeding means is a pivotally mounted tilttable molten metal reservoir provided with a pouring edge coincident with such pivotal axis and having a calculated interior confirmation so related to the location of the pouring edge that in moving the reservoir angularly about its tilt-pivot from one position to another molten metal is delivered to the distributer in fixed relation to the rate of discharge of molten metal from the distributer to the mold. The apparatus also preferably includes means for angularly tilting the distributer slightly from the horizontal to increase or decrease the velocity of the discharge of molten metal from the discharge end of the distributer, to correct as much as possible any difference between the velocity at which the molten metal reaches the mold and the peripheral velocity of the inside of the mold. Preferably also the operative connection between the mold and the reservoir for controlling the feeding of metal from the reservoir to the distributer

in constantly maintained predetermined relation to the rate of relative movement between mold and distributer, includes a means for permitting a lost motion at the commencement of a casting operation, to permit the reservoir to be sufficiently tilted and to permit the metal thereby delivered to the distributer to reach the spout end of the latter, before relative movement is commenced between the mold and distributer. Preferably the apparatus also includes a plate or the like, directly connected to the operating means for synchronizing relative movement between mold and distributer and tilting movement of the reservoir and directly pivoted on said pivot axis and in turn having the reservoir pivotally mounted thereon, whereby tilting of the plate tilts the reservoir, and also includes a part on the plate and a co-acting part on the reservoir for acting as an index to signal when the reservoir is filled with molten metal to the predetermined maximum, irrespective of the presence of previously congealed molten metal in the reservoir.

The invention will be more clearly understood from the following description, when taken in connection with the accompanying drawing, showing the preferred apparatus which may be used to facilitate carrying out the process of the present invention.

In this drawing,

Figure 1 is a vertical axial sectional view of the entire apparatus, partially in section;

Fig. 2 is an enlarged detail view showing in side elevation and on enlarged scale the parts at the right hand end of Fig. 1, including the right hand end of the distributer, parts of the means which operatively connect tilt plate and reservoir to the sliding mold, such tilt plate and reservoir and the index;

Fig. 3 is a transverse vertical section taken on line 3-3 of Fig. 2;

Fig. 4 is a fragmentary view, being a transverse vertical section taken on line 4-4 of Fig. 2;

Fig. 5 is an end elevation of the distributer at its spout end, the arrow indicating the direction of rotation of the mold;

Fig. 6 is a top plan view at the end of the distributer shown in Fig. 5;

Fig. 7 is a side elevation of such end of the distributer, viewed as said end is viewed in Fig. 1; and

Fig. 8 is an enlarged detail view showing the part of the operative connection between the reservoir and the sliding mold for affording the initial lost motion described.

A rotary mold 9 is suitably mounted for as rapid rotation as desired, on ball bearings or the like (not shown) properly supported; the mold being sleeved by a jacket construction 10 and carrying beyond such jacket construction a gear 11 or the like by which

the mold may be power driven. The jacket may serve for water-cooling the mold from end to end. At its left end the mold has inserted therein an annulus 12, which may act, if used, as a carrier for an annular shelf 70 for preventing the loss of molten metal beyond the ends of the mold, for holding in place a core for forming a bell end on the article cast, for forming a convenient extraction means for the article after being cast or 75 for any other purpose well known in the art. The jacket construction 10, in which the mold is suitably mounted to restrain the latter against relative movement lengthwise of the jacket construction, is in any familiar way 80 supported on a base member 13 to permit sliding the mold lengthwise on the base member.

A distributer 14 is provided, this distributer constituting an open-topped gutter 85 carrying a canal 15 running lengthwise of the distributer, and of the mold, which latter is arranged coaxial with, or on an axis parallel to, the axis of the distributer. Near its right hand end the distributer is secured 90 in a supporting standard 16 mounted on base member 13 and open at its top, as indicated most clearly in Fig. 3, over the part of the canal passing through the support. The left hand end of the distributer is 95 formed as a separate piece 17, which may advantageously be made of hard molded carbon. This piece 17 has a canal therein, constituting the discharge spout of the distributer, shaped as shown in Figs. 5, 6 and 100 7, and which may be most briefly described as lying substantially coincident with approximately a one-quarter turn of a helix of considerable pitch. It will be understood that when molten metal is delivered 105 through the canal 15 of the distributer 14 to the spout of the piece 17, the metal will be discharged from the spout into the rotating mold 9 at one side only of the axis of the mold and so as to approach the inside of 110 the mold substantially tangentially.

A means for feeding metal continuously to the end of the distributer partially surrounded by the standard 16, to cause a continuous outflow of such metal from the 115 spout into the mold, includes a tilt plate 18 pivotally mounted above the distributer transversely of the apparatus as indicated at 19 on a cross web 20 offset from one end of the standard 16; a reservoir 21, having 120 substantially the form of a 90° segment of a cylinder, and pivotally mounted on the tilt plate 18 by means of a gudgeon arrangement indicated at 22 in Figs. 2 and 4, and having a central limited pouring channel 125 and edge 23 below the top of the tilt plate 18, the tilt plate being cut away at 24 in registry with such pouring edge; and a worm gear 25 keyed on the pivot shaft to the tilt plate and a worm 26 fixed on a 130

vertical shaft 27 meshing with the worm gear.

In order to predetermine that the amount of metal delivered to the distributor from the reservoir, on raising the tilt plate 18 and consequently the reservoir, (the latter moving toward the dot-and-dash line position shown at 21' in Fig. 2, on rotation of the shaft 27,) will always and from beginning to end of each casting operation exactly compensate for the amount of metal at that instant being discharged from the spout of the distributor, the pouring edge 23 of the reservoir is so calculated and located, the reservoir is of such cross section in all planes including the axis of tilt, and the speed of sliding of the mold is so related to these factors as to attain the desired predetermination. In the first place, the end walls of the reservoir are parallel and perpendicular to the axis of tilt, the side wall of the reservoir below such axis is plane and the only other wall of the reservoir is curved according to a true circle on a radius terminating at the axis of tilt and as long as said plane wall. As a result, in any degree of tilt of the reservoir 21 during movement from the position shown to that indicated at 21' in Fig. 2, the liquid level of the molten metal in the reservoir is of a constant area. In the second place, the rate of continuous tilt of the reservoir during continuous sliding of the mold 9 to the left of Fig. 1 after the commencement of the casting operation with the parts arranged as shown in Fig. 1, is properly predetermined by means of the following operative connections between the reservoir tilt axis and the mold. These operative connections include, in addition to the worm gear 25, the worm 26 and the vertical shaft 27, a bevel gear 28 fast on the lower end of shaft 27, a bevel gear 29 meshing with the bevel gear 28 and fast on a horizontal shaft 30, a bevel gear 31 fast on the other end of shaft 30, a bevel gear 32 meshing with the bevel gear 31 and adapted to be rotated with a transverse shaft 33, and a spur gear (not shown) fast on the shaft 33 and meshing with a rack 34 fast on the underside of the jacket construction 10 which carries mold 9.

In order to afford a slight lost motion at the commencement of a casting operation, to allow the distributor preliminarily to act to permit the metal thereby delivered to the distributor to commence discharging into the mold at the instant of commencement of sliding movement of the mold, means are provided for affording this lost motion in such way that the reservoir 21 is slightly tilted to fill the canal 15 in the distributor from end to end and to cause an overflow into the spout at the instant when the mold commences to slide to the left of Fig. 1. This means is provided by keying, as shown

most clearly in Fig. 8, the bevel gear 32 to the transverse shaft 33 in such a way that a key 35 on shaft 33 has a certain amount of play in a circular recess 36 cut in the hub of gear 32. As a result, on starting to drive the operating means at the commencement of a casting operation, the shaft 30 and consequently the pivot axis 19 will perform a slight rotation before shaft 33 commences to rotate; shaft 33 thereafter, however, rotating continuously with shaft 30.

In order to provide a means for predetermining precisely, just before a casting operation, the instant when reservoir 21 is filled to the predetermined maximum, means are provided, in coaction with the mounting of the reservoir on tilt plate 18 by means of the gudgeon 22, including a part 37 fixed on the tilt plate and a co-acting part 38 fixed on the reservoir and forming the scale or plunger arm of a spring scale 39 carrying a fixed suitably calibrated dial 40 over which an index 41 is moved by the plunger 38 to indicate the weight of metal at any instant in the reservoir. By this means it is a simple matter to predetermine the exact contents of the reservoir by weight; and even where the refractory lining of the reservoir has adhering thereto particles or masses of prematurely congealed metal, as may be the case after several casting operations, the weight of such adhering metal may be allowed for by using the spring scale mechanism according to the well known principles of calculating tares.

In order to affect the rate of flow of metal from the spout of the distributor, as an auxiliary to such rate as affected solely by the speed of tilt and dimensions of the reservoir 21, means are provided for inclining the entire apparatus relative to the horizontal and to maintain the apparatus in such inclination during a casting operation. Such means includes a center pivotal support 42 and end jacks 43 as shown in Fig. 1.

I claim:

1. The process of casting an annular metallic article in a rotary mold on a substantially horizontal axis which consists in laying the metal in the mold in successively deposited spirally related subdivisions while guiding the flow of the metal adjacent to the mold to cause the metal to flow in a limited sheet sidewise of the mold axis.

2. The process of casting an annular metallic article in a rotary mold on a substantially horizontal axis which consists in laying the metal in the mold in successively deposited spirally related subdivisions while guiding the flow of the metal adjacent to the mold to cause the metal to flow into the mold only at one side thereof at an angle to the mold axis with such angle in a plane substantially transverse to the mold axis.

3. The process of casting an annular me-

- 5 tallic article in a rotary mold on a substantially horizontal axis which consists in laying the metal in the mold in successively deposited spirally related subdivisions while guiding the flow of the metal adjacent to the mold to cause the metal to flow to approach the mold substantially tangentially at one side of the mold axis only.
4. The process defined in claim 1, wherein 10 also the flow of metal is subjected to pressure sufficient to cause the limited sheet to reach the mold at substantially the same velocity as the peripheral velocity of the inside of the mold.
5. The process of casting an annular metallic article in a rotary mold on a substantially horizontal axis which consists in laying the metal in the mold in successively deposited spirally related subdivisions while 20 guiding the flow of the metal first substantially axially of the mold and then angularly diverting the flow of the metal to discharge the same as a substantially solid stream to one side of the mold.
6. The process of casting an annular metallic article in a rotary mold on a substantially horizontal axis which consists in laying the metal in the mold in successively deposited spirally related subdivisions while 30 guiding the flow of the metal adjacent to the mold to cause the metal to flow against the mold at substantially the same velocity as the peripheral velocity of the inside of the mold.
7. The process defined in claim 5, wherein the axis of rotation of the mold is tilted to affect the velocity of discharge of the metal into the mold.
8. In a rotary casting machine, the combination of a rotary mold, a metal distributer adapted to project inside the mold and constructed and arranged for continuously discharging molten metal inside the mold, operating means for moving the distributer 40 and mold relatively lengthwise to the mold, movable feeding means for delivering molten metal to the distributer adapted to be moved to control the rate of delivery of molten metal to the distributer, and means controlled by the relative movement of either distributer or mold and operatively connected to the feeding means for moving the latter constantly to supply molten metal from the feeding means to the distributer 50 in definite relation to the rate of discharge of molten metal by the distributer into the mold.
9. The casting machine defined in claim 8, wherein the last mentioned means includes 60 a driving element and a complementary driven element arranged to permit initial lost motion between said elements to defer relative movement between the mold and distributer for a predetermined interval of time to permit metal to be delivered from
- the feeding means to the distributer and to be discharged from the distributer into the mold approximately at the instant when said relative movement commences.
10. The casting machine defined in claim 70 8, wherein the distributer is an elongated member provided with a lengthwise canal, wherein the feeding means is arranged to deliver molten metal to the canal adjacent to one end of the latter, and wherein the 75 canal at the opposite end of the distributer is angularly bent to one side only of the axis of the mold and terminates in an open spout adapted to direct the molten metal discharged from the distributer in a stream 80 substantially tangentially striking the mold.
11. The casting machine defined in claim 10, wherein the bent part of the canal is substantially C-shaped, transversely of the mold axis.
12. The casting machine defined in claim 85 11, wherein the bent part of the canal is C-shaped in top plan.
13. The casting machine defined in claim 10, wherein the bent part of the canal is 90 substantially coincident with approximately a one-quarter turn of a helix.
14. The casting machine defined in claim 8, wherein the feeding means has a pivotally mounted tilttable molten metal reservoir 95 provided with a pouring edge and having a calculated interior conformation so related that in moving the reservoir angularly about its tilt pivot from one position to another molten metal is delivered to the distributor in fixed relation to the rate of discharge of molten metal from the distributor by way of the spout.
15. The casting machine defined in claim 14, wherein the pouring edge of the reservoir 105 in each tilted position thereof is coincident with the pivot axis of the reservoir.
16. The casting machine defined in claim 15, wherein the reservoir when filled to a predetermined maximum holds its contained 110 molten metal below said edge and the interior of the reservoir is so shaped that in all tilted positions of the reservoir the molten metal level at any instant opposite the pouring edge is of the same area as the level 115 thereof at any other instant irrespective of the degree of tilt of the reservoir.
17. The casting machine defined in claim 16, wherein the reservoir is provided, as its 120 total complement of metal-holding walls, with a substantially plane side wall below the pouring edge when the reservoir is filled to the predetermined maximum, with a circularly curved side wall, the radius of which terminates at all times at a center coincident with the pivotal axis of the reservoir, and with opposite end walls.
18. The casting machine defined in claim 17, wherein a lift plate is provided and directly pivoted on the tilt axis of the reser- 125
- 130

- voir and directly actuated by said means controlled by said relative movement between mold and distributer, and wherein the reservoir is attached to the lift plate.
- 5 19. The casting machine defined in claim 18, wherein in certain of its parts said lift plate is prolonged beyond the pouring edge of the reservoir and beyond said pivotal axis to limit the upflow of molten metal 10 from the reservoir and the outflow thereof over said edge.
20. The casting machine defined in claim 14, wherein means are provided including a pivotal mounting between the reservoir and 15 lift plate and a part on the plate and a co-acting part on the reservoir, for acting as an index to signal when the reservoir is filled with molten metal to a predetermined maximum irrespective of the presence of previously congealed molten metal in the reservoir.
21. The casting machine defined in claim 19, wherein one of the parts of the last mentioned means includes a spring-held scale- 25 member, a calibrated scale, and an index moving over the scale controlled by said member.
22. The casting machine defined in claim 1, wherein means are provided for angularly 30 tilting the mold and distributer slightly from the horizontal to increase or decrease the velocity of discharge of the molten metal from the spout end of the distributer.
23. The casting machine defined in claim 35 8, wherein the operating means between the movable one of the mold and distributer and the feeding means includes a means for affording a lost motion at the commencement of a casting operation, to allow the 40 feeding means preliminarily to act to permit the metal thereby delivered to the distributer to commence discharging into the mold
- at the instant of commencement of relative movement between mold and distributer.
24. In a rotary casting machine, the combination of a rotary mold, a metal distributer adapted to project inside the mold and constructed and arranged for continuously discharging molten metal inside the mold, operating means for moving the distributer 45 and mold relatively lengthwise of the mold, movable feeding means for delivering molten metal to the distributer adapted to be moved to control the rate of delivery of molten metal to the distributer, and operating means for moving the movable feeding means.
25. The casting machine defined in claim 24, wherein means are provided operatively connected to one of said operating means to 60 be actuated thereby in turn to actuate the other operating means at a predetermined instant and for a predetermined length of time bearing a fixed relation to the commencement and duration of operation of 65 said one of said operating means.
26. The casting machine defined in claim 24, wherein the feeding means includes a tiltable molten metal reservoir provided with a pouring edge and having a calculated 70 interior conformation so designed that in tilting the reservoir from one position to another molten metal is delivered to the distributer in fixed relation to the rate of discharge of molten metal from the distributer. 75
27. The casting machine defined in claim 26, wherein the interior of the reservoir is so shaped that in all the various tilted positions thereof the molten metal level is of the 80 same area.

In testimony whereof I affix my signature.

DIMITRI SENSAUD DE LAVAUD.
